UNITED STATES PATENT OFFICE.

GEORGE B. FULLER, OF ARKONA, ONTARIO, CANADA, ASSIGNOR TO WESTINGHOUSE ELECTRIC & MANUFACTURING COMPANY, A CORPORATION OF PENNSYLVANIA.

SHUNT BLOWOUT DEVICE.

Application filed July 22, 1927. Serial No. 207,590.

The invention relates, generally, to magnetic blowout devices and especially to magnetic blowouts for switches.

In multiple-unit-train operation, it may happen that, after the train has pulled into the yards and stopped, the third-rail shoes on one or more cars are not in contact with the third rail. Under this condition, or, if a shoe fuse happens to be out, a current of small magnitude for lighting, heating and the operation of a compressor motor may flow through some of the bus-line switches in a direction opposite to normal. This relatively small reversed current, flowing through the few turns of a series blowout coil, is incapable of demagnetizing the pole pieces and the core of the blowout coil after they have been magnetized by the comparatively large motor current which flows when the train is in operation. Thus, when the switch is open, there is no magnetic action present to blow the arc out and, in some cases the residual magnetism in the pole pieces and blowout core is of sufficient strength to blow the arc back into the switch-actuating mechanism. The same is true of any switch in which it is desired to interrupt a small current after a heavy current has been passed in the opposite direction.

The object of the invention, generally stated, is to provide an arc-rupturing device which will be simple and reliable in operation and designed to subject an arc to a magnetic-blowout influence in the desired direction, regardless of the direction of flow or magnitude of the current.

A further object of this invention is to provide for maintaining an arc-rupturing field for a desired interval after the switch jaws have been separated.

Other objects of the invention will be apparent to those skilled in the art when the following description is considered.

For a clearer understanding of the invention and the operation of its parts, reference may be had to the following description which should be read in conjunction with the accompanying drawing, in which;

Figure 1 is a front elevation of a pneumatically operated switch showing an arrangement of blowout coils in accordance with the invention.

Fig. 2 is a side elevation of the switch,

Fig. 3 is a circuit diagram showing the connection of the blowout coil in accordance with the invention,

Fig. 4 is a circuit diagram showing connections in a modified form of the invention,

Referring now to Figs. 1 and 2, a switch 10 comprises a pair of jaws, one of which is disposed for movement to perform switching operations. The movable jaw, which is located below the other jaw, is disposed to be actuated by an air engine 11 of any suitable type well known in the art. As shown, a magnet valve is provided for controlling the operation of the air engine and the lower switch jaw for transmitting motion to the latter.

An interlock member 13 is attached rigidly to the connecting rod 14 and disposed to move vertically with it. In the embodiment illustrated, the interlock member comprises a block of insulating material on which a number of contact plates 15 are mounted. The contact plates 15 are disposed to make contact with contact fingers 16 when the switch jaws are moved into engagement. The contact plates carried by the block, are located to engage the contact fingers immediately after the initial closing movement of the lower jaw from its full-open position and are retained in engagement continuously as long as the switch remains closed.

The switch 10 is enclosed by an arc-chute 17 which is disposed to confine arcs that may be drawn between the switch jaws. Iron pole pieces 18 are attached to the sides of the arc-chute 17 and serve to concentrate the magnetic flux generated when the blowout coils 19 are energized, thereby providing a desired arc-rupturing field.

Referring now to Fig. 3, it will be seen that the blowout coil is disposed in shunt to the switch 10. A shunt circuit around the switch 10 is completed through the contact fingers 16 and contact plates 15 immediately after the initiation of the movement of the lower switch jaw toward its closed position. In order to reduce arcing and to insure the proper duration of the arc-rupturing field when the switch is opened, the contact plates 15 and contact fingers are disposed to remain in engagement for a short interval after the initial separation of the switch jaws. A resistor 20 is inserted in the shunt circuit and serves to limit the flow of current through the blowout coil particularly after the switch jaws have separated and before the interlock contacts have separated, thereby preventing an arc from occurring at the interlock contacts. It will be seen that, while the switch 10 is closed,

the blowout-coil circuit is short-circuited and practically no current will flow through it.

In operation, when an opening movement of the switch is initiated and the switch jaws are separated slightly, the blowout coil is excited by the sudden increase of current flowing through it, and an arc-rupturing field is established. During the opening of the switch, since the jaws are disposed to make rolling contact, the rear portions of the jaws separate first and the point of contact moves gradually toward the tip at which point an arc may be drawn. When an arc is drawn at the tip it is forced outward and lengthened through the action of the blowout field on the field surrounding the arc.

It will be readily understood that this magnetic blowout action is effective, irrespective of the direction the current flows through the switch, since, with a reversal of the main current, a reversal of its field occurs and, simultaneously, a reversal of the blowout field occurs. In addition to being subjected to a magnetic blowout action, the arc is confined 25 within the arcing chute.

In the use of shunt blowout coils, it is possible to provide a sufficient number of turns in the coil to effectively magnetize the pole piece with a very small current. It will also be seen that, as the jaws separate and the arc is drawn out, the resistance of this path increases so that a greater current will flow through the shunt blowout coil and thereby develop an increasing arc-rupturing field.

35 However, the resistor 20, connected in series with the blowout coil will prevent the current from increasing to such magnitude as to cause arcing at the interlock contact plates when the blowout-coil circuit is broken.

40 In Fig. 4, a compound coil arrangement is shown. The operation in this case is similar to that described, hereinbefore and the series coil serves to boost the strength of the blowout field established by the shunt blowout coil.

45 Since the application of this invention is not limited to the type of switch described, it is desired that the embodiment described hereinbefore be considered illustrative and not in a limiting sense.

50 I claim as my invention:

1. In a circuit-interrupting device, in combination, a switch, arc-rupturing means provided with a blowout coil associated with the switch, a circuit for shunting the switch, said blowout coil being connected in the shunt circuit, and an interlock disposed to control the shunt circuit, said interlock being disposed to maintain the shunt circuit closed after the initial opening of the switch.

60 2. In a circuit-interrupting device, in combination, a switch, arc-rupturing means provided with a blowout coil associated with the switch, means for maintaining a magnetic blowout field for an interval after the separation of the switch jaws, a circuit for shunt-

ing the switch comprising the blowout coil, a resistor and an interlock for controlling the circuit.

3. In a circuit-interrupting device, in combination, a switch, arc-rupturing means provided with a blowout coil associated with the switch, a circuit for shunting the switch, said blowout coil being connected in the shunt circuit, means for limiting the flow of current through the shunt circuit and an interlock disposed to control the shunt circuit, said interlock being disposed for the operation with the switch and to maintain the shunt circuit closed after the initial opening of the switch.

4. In a circuit-interrupting device, in combination, a switch, arc-rupturing means provided with a blowout coil associated with the switch, a circuit for shunting the switch, said blowout coil being connected in the shunt circuit, an interlock disposed to control the shunt circuit and a resistor connected in series with the blowout coil in the shunt circuit, said resistor disposed to limit the flow of current in the shunt circuit and reduce arcing at the interlock contact.

5. In a circuit-interrupting device, in combination, a switch, arc-rupturing means provided with a blowout coil associated with the switch, a circuit for shunting the switch, said blowout coil being connected in the shunt circuit, means for limiting the flow of current through the shunt circuit and an interlock disposed to control the shunt circuit, said interlock comprising an insulating block disposed to be actuated by the switch, said switch giving vertical motion to the insulating block, when operated, a plurality of contact plates attached to the insulating block, a plurality of contact fingers disposed to engage the contact plates, such engagement existing while the switch is closed and continuing for a predetermined interval after separation of the switch jaws.

6. In a circuit-interrupting device, a switch, arc-rupturing means provided with a blowout coil, said blowout coil being connected in parallel-circuit relation to the switch, and interlocking contact members operated by the switch for controlling the energization of the blowout coil, said interlocking contact members disposed to remain in their circuit-closing position for an interval of time after the initial opening of the switch.

7. In a circuit-interrupting device, a switch, arc-rupturing means provided with a blowout coil, said blowout coil being connected in shunt relation to the switch, and means for energizing the blowout coil for a predetermined period of time after the initial opening of the switch, whereby an arc-rupturing field is maintained after the operation of the switch.

In testimony whereof, I have hereunto subscribed my name this 11th day of July, 1927.

GEORGE B. FULLER.
